(57) **CLAIM**

The ornamental design for a shirt with sleeves, as shown and described.

DESCRIPTION

FIG. 1 is a right front perspective view of a shirt with sleeves according to the present design;

FIG. 2 is a front view thereof;

FIG. 3 is a back side view thereof;

FIG. 4 is a right side elevation view thereof; and,

FIG. 5 is a top plan view thereof.

The evenly spaced broken lines shown in the drawings are directed to environment, are for informational purposes only, and form no part of the claimed design.

The surface shading on the claimed portion is provided only to indicate the character and/or any contour or curvature of the surfaces. They do not indicate color, texture, markings that actually exist thereon, indicia, graphic representations, surface treatment, or any other ornamentation applied to the article.
